UNITED STATES PATENT OFFICE.

ERNEST E. KOKEN, OF ST. LOUIS, MISSOURI.

CHAIR.

SPECIFICATION forming part of Letters Patent No. 548,258, dated October 22, 1895.

Application filed May 13, 1895. Serial No. 549,062. (No model.)

To all whom it may concern:

Be it known that I, ERNEST E. KOKEN, of St. Louis, Missouri, have made a new and useful Improvement in Chairs, of which the following is a full, clear, and exact description.

The improvement relates chiefly to revolving and reclining chairs of the class known as "hydraulic."

The features of the improvement will be hereinafter set forth, and designated in the claims.

In the annexed drawings, making part of this specification and exhibiting the most desirable mode of carrying out the improvement, Figure 1 is a vertical longitudinal section of that portion of the chair to which my improvement particularly relates along the line 1 2, Figs. 4, 5, 7, and 8, and represents the piston and the plunger empty and in their lowest positions, with the valves open and the piston unlocked. Fig. 2 is a similar view of the same parts, showing the piston somewhat elevated and the plunger therein at the end of its upstroke and locking the piston in place, the valves being closed and the piston and cylinder charged with fluid. Fig. 3 is an end elevation of the bottom of the plunger and the valve-lever pivoted thereto. Fig. 4 is a horizontal cross-section along the line 4 4, Fig. 1. Fig. 5 is a horizontal cross-section along the line 5 5, Fig. 2. Fig. 6 is in part an elevation of the cylinder and piston and in part a vertical section of the chair-seat and connected parts and the shafts for communicating motion to the chair mechanism. The portion of the chair-support surrounding the spindle is also shown in vertical cross-section. Fig. 7 is a plan view of the top of the piston and mechanism therein and therewith connected. Fig. 8 is a similar view with parts broken away. Fig. 9 is a vertical section of the top of the piston and contained parts along the line 9 9, Fig. 8. Fig. 10 is a longitudinal cross-section of a lever for operating the chair mechanism along the line 10 10, Fig. 11. Fig. 11 is a longitudinal cross-section along the line 11 11, Fig. 10. Fig. 12 is a rear elevation of the top of a pitman connecting the plunger with a crank-shaft. Fig. 13 is an enlarged detailed vertical longitudinal section along the line 1 2, Figs. 4, 5, 7, and 8, showing the relations of the parts

when the head of the piston is opposite the annular recess g^6 , the plunger H being at the extreme end of its downstroke; and Fig. 14 shows the relations of the same parts when the piston is in the same position and the plunger is at the end of its ordinary upstroke. The manner in which the fluid flows back into the piston during the downstroke of the plunger when the piston is in the position illustrated in Fig. 13 is indicated in said figure by arrows.

Similar letters refer to similar parts throughout the several views.

The chair, Fig. 6, in connection with whose foot-rest and seat my improvements are shown is of the type known as "barber's chair," the improvement being more especially applicable thereto. By means of it the chair, while revolvable in the preferred form, may be raised and lowered so as to adapt it to the size of the occupant or the barber using it and may be locked in position and the chair-back and foot-rest inclined and adjusted as may be needed.

The chair-base A, seat B, back C, arms D, and foot-rest E are of familiar construction and hardly require a detailed description, saving to say that the base A, including the parts not shown, may be of any ordinary construction, that the back is pivoted at its lower end c to the seat-frame, the foot-rest E is, by means of arms e , pivoted at e' to the seat-frame, and the arms D at their ends, respectively, are jointed to the back C and to the extended foot-rest arms, so that when the back is turned downward the foot-rest is turned upward and when the back is raised the foot-rest is dropped. From the rear of the foot-rest two lugs e^2 e^3 are shown projecting backward, and between these the rod E' is shown pivoted, Figs. 6 and 7. When the chair-back and foot-rest are adjusted, they may be held in position by locking the bar E' in place.

F, Figs. 1, 2, 4, 5, 6, and 9, represents a piston upon which the chair-seat is mounted, Fig. 6, and G, Figs. 1, 2, 4, 5, and 6, represents a cylinder within which the lower end of said piston turns and reciprocates.

The cylinder G is open at the top and closed at the bottom. A screw-threaded opening g is preferably formed in the bottom and is closed by a screw-plug g' . At its top it is

preferably provided with a substantially horizontal annular flange g^2 , having a substantially vertical rim g^3 . It is preferably somewhat larger than the head of the piston near 5 its bottom, as shown at g^4 . At the highest point to which the piston is intended to be elevated while the chair is in use a vertical recess g^5 is formed on the inside of the cylinder, and above that point an annular groove 10 g^6 is formed in its inner side. It is shown surrounded by the central portion of the chair-base and with its flange g^2 resting upon the top of the base; but no special method of attachment is essential.

15 The hollow piston F, Figs. 1, 2, 4, 5, and 6, is preferably provided with a head f . Where the cylinder used contains the recess g^5 , the head of the piston is preferably made thinner than the height of said recess, so that when 20 its face is raised just above the bottom of said recess its upper edge will be below the top of said recess. Above the piston-head there is an annular recess f' , which is preferably connected with the interior of the piston by one 25 or more perforations f^2 and one or more perforations f^3 , located above the perforations f^2 . The side of the piston is also pierced by an opening f^4 , in which is located a wedge f^5 , having its thicker end uppermost. On one 30 side of the piston a vertical recess f^6 is also preferably formed, in which is located a dog f^7 , and behind the dog a spring f^8 , which tends to press the upper end of the dog outward. The bottom of the piston F contains a fluid- 35 passage f^9 , closed by a valve F' , having guides f^{10} , &c., fitting said opening f^9 , a valve-stem f^{11} , extending upward, provided with a head f^{12} , and a coiled spring f^{13} , whose lower end is preferably seated in a recess f^{14} in the interior of the bottom of the piston, and whose 40 upper end rests against the under side of said valve-stem head f^{12} and tends to keep said valve F' seated against its seat f^{15} , formed on the bottom of the piston.

45 The top F^2 of the piston F is shown enlarged to make room for mechanism hereinafter described. It is preferably cut away at f^{16} to facilitate the insertion of parts of my device and perforated at f^{17} to permit of the 50 passage of the bar E' through it. It is preferably provided with an annular shoulder f^{18} , which rests on the flange g^2 of the cylinder G when the piston is in its lowest position. The bottom of the piston I prefer not to allow to 55 touch the bottom of the cylinder G, as it is desirable to leave room for the opening of the valve F' when the piston is at its lowest point. From one side of the top F^2 of the piston extends the horizontal lug g^{19} , Fig. 6, 60 whose use will be hereinafter described.

Within the piston F a plunger H, Figs. 1, 2, 3, 4, and 5, reciprocates. It is shown hollow, open at the top and closed at the bottom, and containing fluid-passages h^4 through 65 its sides and a fluid-passage h^5 through its bottom. From its bottom two lugs h^6 h^6 preferably project, between which a lever H'

is pivoted. This lever carries on one end a valve h^7 , which seats upward at h^8 and closes the fluid-passage h^5 . At its other end h^9 it 70 carries a downwardly-projecting lug h^{10} , and at that end is preferably sufficiently heavy to overbalance the end carrying the valve h^7 , and cause said valve to seat in the absence of any counteracting force. Around the outside of the plunger H there is an annular recess h^{11} , which the fluid-passages connect with the interior of the piston, and on one side a recess h^{12} , deeper at top than at bottom, and whose face h^{12a} is adapted to make 75 contact with the sloping inner side of the wedge f^5 , is formed. Across the head of the plunger H there extends a cross-bar h^{13} . To the bar h^{13} is pivoted the lower forked end of the pitman I. The upper end of the pitman 80 is formed into the crook i, whose upper end is connected to the crank k of the crank-shaft K by its wrist-pin k' . The crook i enables the pitman I to avoid the crank-shaft and assume a vertical position at the end of the up-stroke, at which time the plunger acts upon the wedge f^5 and the greatest power is needed. The pitman I is also bent at i' to bring it into a central position in the piston. (See Fig. 12.)

The crank-shaft K is preferably hollow and 85 is journaled in bearings at k^2 and k^3 . At its outer end it carries an arm k^5 , preferably beveled at the corner k^6 , and in the form shown is provided with a socket k^7 for the reception of a bolt.

To the shaft K is attached an arm K^2 . (Shown in full lines in Fig. 6,) in its lowest position. Through a screw-threaded hole in this arm K^2 passes a set-screw k^9 , which is prevented from turning when in position by 105 the jam-nut k^{11} . The arm K^2 is directly over the rim g^3 of the cylinder G when near its lowermost position and the lower end of the set-screw k^9 is in position to strike the lug g^{19} when the arm K^2 is turned low enough. The 110 point at which the screw k^9 will strike the lug g^{19} may be regulated by screwing it in or out, as will be obvious.

Through the crank-shaft K passes a shaft L, Figs. 1, 2, 6, 7, 8, 9, 10, and 11, which extends beyond the inner end of the crank-shaft, and its own inner end l is shown journaled in bearings l' l' , formed in or attached to the top F^2 of the piston. Along a section l^2 within the top of the piston the shaft L is screw-threaded, and between that section and its bearings l' l' there is a part l^3 , which is shown smaller in cross-section than the part l^2 . The part l^2 carries a substantially-vertical plate M, Figs. 7, 8, and 9, pierced by an opening through which the shaft L passes and having said opening screw-threaded and engaging the thread on section l^2 . This plate M preferably has attached thereto four bolts, one located near each corner. The two upper 130 ones are lettered m m and the two lower ones m' m' . All of said bolts are provided with heads m^2 . The two lower bolts are preferably shortest. The bolts m m and m' m' pass

through bolt-holes m^3 in a plate M' , and through an opening in that plate the part l^3 of the shaft L passes, and said bolts connect the plate M' with the plate M . The shaft-hole 5 and bolt-holes through the plate M' are preferably large enough to allow the plate M some play. Between the heads m^2 of the bolts m and the plate M' a coiled spring m^4 surrounds each of the bolts m and tends to press the 10 plate M' inward toward the plate M . The faces of the plates M and M' are shown grooved transversely by grooves m^5 m^6 , arranged opposite each other and adapted to receive and fit the sides of the bar E' , which 15 bar passes between the plates M and M' and is in part supported in said grooves m^5 m^6 .

The outer end of the shaft L carries a lever N , Figs. 6, 7, 10, and 11, which is attached thereto. The lever N is preferably provided 20 with a recess n at its inner end, within which the arm k^5 of the crank-shaft K is located, and the sides n' n^2 of said recess answer as stops limiting the movement of the lever N independent of the arm k^5 of the shaft K . 25 The lever N , as shown, contains a bolt n^3 , reciprocating longitudinally in said lever and adapted to engage the recess k^7 in the arm k^5 of the crank-shaft. It is preferably beveled in the form shown at n^4 , so as to enable it to 30 ride up over the arm k^5 when struck by the beveled corner k^6 of said arm. From the bolt n^3 a rod n^5 leads to the button n^6 , which tends to limit the inward movement of the bolt and enables it to be retracted. The bolt n^3 is 35 pressed inward by the coiled spring n^7 , which at its outer end rests against a shoulder in the lever and at its inner end against said bolt. The lever N is preferably attached to the shaft L by making the part l^3 near the 40 outer end of said shaft conical at the point where the lever N is attached to it and screw-threading its extreme outer end, and forming a socket n^8 in the lever corresponding in shape to the part l^3 of the shaft to receive said 45 part, and fastening the lever and shaft together by screwing a nut n^9 onto the end of the shaft. This enables me to obtain a very rigid connection without the use of a key and allows radial adjustment of the lever.

50 The operation of my improved chair is as follows: Supposing the parts to be in the position shown in Fig. 1, and the cylinder and piston charged with fluid, preferably oil, and the lever N being in the horizontal position 55 shown in full lines in Fig. 7, an operator wishing to elevate the chair-seat should grasp the lever N and pull it toward a vertical position, but preferably not quite to a vertical position, as it is not desirable to bring the plunger H 60 into contact with the wedge f^5 . This movement of the lever turns the crank k toward the position shown in Fig. 2 and elevates the pitman I and the plunger H . As soon as the lugs h^6 h^6 , projecting down from the bottom 65 of the plunger H , are lifted out of contact with the head f^{12} of the valve-stem f^{11} of the valve F' the spring f^{13} causes the valve F' to seat

and close the fluid-passage through the bottom of the piston F . During the upward passage of the plunger H the atmospheric and 70 fluid pressure above the valve h^7 is sufficient to counterbalance the weight of the outer end of the lever H' and cause the valve h^7 to open and permit the fluid above the plunger to pass down into the space between the bottom 75 of the plunger and the bottom of the inside of the piston. At the end of the upstroke the pressure upon the face of the valve h^7 becomes equalized by the pressure on its under side and the weight of the outer end of the lever 80 H' causes the valve h^7 to seat. At this time the valves are in the positions shown in Fig. 2. The next step is to reverse the movement of the lever and push it back toward, but not quite into, its original position, as it is not 85 desirable to open the valve h^7 and the valve F' simultaneously during the elevation of the chair, as that would permit the oil or other fluid beneath the piston to pass back into the piston. The limits of the stroke are soon 90 learned by experience. This downstroke of the plunger, by increasing the fluid-pressure above the valve F' , forces that valve open and forces a portion of the fluid in the piston F through the fluid-passage f^9 in the bottom 95 of said piston into the bottom of the cylinder beneath the piston, and thus forces the piston upward. The motions of the lever already described are repeated as often as may be necessary in order to elevate the chair-seat mounted 100 on the piston to the desired height. When that point is reached, the piston is locked in position so as to prevent it from either turning or moving vertically on the last upstroke of the plunger by pulling the lever into a vertical position and bringing the pitman and the plunger connected to the crank-shaft into the position shown in Fig. 2. This brings the face h^{12a} of the recess h^{12} of the plunger H 105 into contact with the inner face of the wedge f^5 and forces the outer face of the wedge f^5 so firmly against the inside of the cylinder G as to lock the piston and cylinder firmly together. By having the crook i in the pitman I , I am able to apply great force at the end of 110 the upstroke just where it is needed in locking the piston. The crook i^2 is useful in making a connection with the cross-bar h^{12} in the center.

When the piston is locked, the parts are in 115 the position shown in Fig. 2. At that time the fluid-passage f^2 is below the bottom of the plunger H , and the annular recess f' above the head of the piston is by means of the fluid-passages f^2 and f^3 connected with the space 120 within the piston both above and below the plunger, which facilitates the disengagement of the plunger from the wedge f^5 , when it is desired to disengage it, by allowing fluid to pass from the space beneath the plunger to 125 the space above it until the bottom of the plunger has passed the fluid-passage f^2 .

In case the piston F is raised high enough 130 in the cylinder to bring the bottom of the pis-

ton above the lower end of the vertical recess g^5 the fluid below the piston is able to pass up through the recess g^5 , Figs. 1 and 2, into the recess f' above the piston-head f , and to 5 pass during the downstroke of the plunger H through the fluid-passages f^2 and f^3 from the recess f' above the head of the piston into the annular recess h^{11} around the outside 10 of the plunger H , and thence into the interior of the plunger through the fluid-passages h^4 , and during the upstroke of the plunger it is able to pass back through the same openings until the bottom of the recess h^{11} is carried 15 above the fluid-passage f^2 , and thereafter is able to pass back through the same passages with the exception of the fluid-passage f^2 , and in consequence of this communication between the space below the piston in the cylinder and the space in the cylinder above the 20 plunger the continued movement of the plunger H has no further effect in elevating the chair-seat.

In case the piston is in any way raised high enough to bring the upper end of the dog f^7 , 25 Figs. 1, 2, and 4, opposite the annular recess g^6 in the cylinder the spring f^8 will force the dog f^7 out into said recess g^6 , and the upper end of the dog coming against the top of the recess g^6 will prevent the further upward 30 movement of the piston.

When it is desired to lower the chair-seat, the lever N is pushed down toward the position shown in Fig. 7, so as to bring the bottom of the plunger H low enough to open the 35 plunger-valve h^7 by bringing the lug h^{10} against the bottom of the chamber in the piston F , and thus forcing the outer end of the lever H' upward and opening the valve F' by bringing the lugs $h^6 h^6$ against the head 40 f^{12} of the valve-stem f^7 , thus pressing the valve F' down from its seat. The fluid below the piston is then able to rise up into the piston and the piston to descend. In Fig. 1 the plunger-valve and piston-valve are shown as 45 far open as the lug h^{10} and lever H' will permit. As will be obvious, the opening may be decreased by widening the distance between the bottom of the plunger H and the bottom of the inside of the piston F until the lug h^{10} 50 is able to assume the position shown in Fig. 2, so as to permit the lever H' to close the valve h^7 altogether and release the valve-stem f^{11} from pressure entirely, so as to allow the valve F' to seat. In proportion to the degree which 55 the valves mentioned are opened will be the rapidity of the flow of the fluid into the piston and the descent of the piston and the chair-seat, and to enable the user of the chair to regulate the rapidity of the descent of the 60 piston the arm K^2 , Fig. 6, and co-operating parts are useful. When the lower end of the set-screw k^9 strikes the lug g^{19} , the motion of the crank-shaft K and the plunger H , connected therewith, are stopped, and the point 65 in the downstroke of the plunger at which its motion will be stopped by the set-screw coming in contact with the lug g^{19} can be regu-

lated within certain limits by simply screwing the set-screw farther in or out. In that way the motion may either be made very rapid 70 on the one hand or very slow on the other, as may be desired.

When the descent of the piston F brings the arm K^2 against the top of the rim g^3 of the cylinder G , the shaft K is caused to turn 75 sufficiently to lift the plunger H high enough to permit the valve F' to close before the shoulder f^{18} strikes the flange g^2 , and thus brings the piston to a stop upon fluid, which prevents the jar which would otherwise be 80 experienced.

Ordinarily the crank-shaft K is rigidly connected with the lever N by means of the arm k^5 and the bolt n^3 , and while thus connected with said lever and through it with the shaft 85 L , to which the lever N is attached, it and the shaft L move together. The movement of the lever on its downstroke, though it turns the shaft L , has no effect upon the plates M and M' , except to force them away from the inner 90 end of the crank-shaft, which motion is immaterial. The motion of the lever N from its lowest position to the vertical position in which it is shown in Fig. 6 in dotted lines, though it draws the plate M' toward the 95 shoulder on the screw-threaded section l^2 of the shaft L , does not bring it quite in contact with that shoulder, and hence has no more effect upon the action of the clutch than the downstroke. When the lever N has been 100 brought to a vertical position, it is prevented from going farther by the wedge f^5 and the pitman I . (See Fig. 2.) In order to unlock the bar E' , it is necessary to disengage the bolt m^3 from the arm k^5 of the crank-shaft. That 105 is done by seizing the button m^6 and pulling the bolt m^3 out of engagement with said crank-shaft arm. As soon as this is done the lever N is free to move independently of the crank-shaft K until the arm k^5 comes in contact with 110 the stop n of the lever. If so moved, the shoulder on the outer end of the screw-threaded section l^2 of the shaft L is brought 115 into contact with the inner face of the plate M' , and the upper edge of the latter is forced 120 away from the inner face of the plate M sufficiently to loosen the bar E' . The back of the chair and foot-rest may then be adjusted. During their adjustment the plates M and M' are able to turn on the shaft L , so as to accommodate 125 their positions to the inclination of the bar E' . When the chair-back and foot-rest have been adjusted, the lever N is pushed back into the perpendicular position, and the plate M is in that way forced far enough inward 130 to disengage the inner face of the plate M' from the shoulder on the shaft L and permit the springs m^4 to press the plate M' inward toward the plate M and thus clamp the bar E' in position.

When the lever N is pushed back in the manner above described toward a vertical position, the beveled face n^4 of the bolt n^3 strikes the beveled corner k^6 , if free to do so, and

rides over the outer end of the arm k^5 until it reaches the socket k^7 , and is then forced into said socket by the spring m^7 . The shafts K and L are thus reconnected and move together again until again disengaged in the manner described.

In Fig. 1 the crank K and pitman I and in Fig. 6 the arm K^2 are shown in dotted lines in the positions they would occupy if the 10 parts were arranged so as to enable the plunger to be operated by moving the lever from the perpendicular down toward the front of the chair instead of toward the back.

I have described the forms of mechanism 15 shown and their mode of operation, but wish it to be understood that the forms described and shown are simply the preferred forms, inasmuch as each and all may be greatly varied in form and many equivalents may be substituted without departing from the essence of 20 my invention, as will be obvious to skilled mechanics reading this specification.

Where I speak in my claims of the piston reciprocating in the cylinder, I wish to include but not to confine myself to the form 25 shown, in which a portion of the upper end of the piston does not enter the cylinder.

I claim—

1. The combination in a chair of a cylinder; 30 a hollow piston reciprocating therein; a chair seat mounted on the piston; means for elevating the piston and chair seat; means for admitting fluid from the cylinder to the interior of the piston; and means which automatically 35 close the piston - valve before the piston reaches a solid bearing, and bring the piston to a stop upon the fluid in the cylinder; substantially as described.

2. The combination of a cylinder; a hollow 40 piston reciprocating therein; an opening in the side of the piston; a wedge in said opening; a plunger reciprocating in said piston, which engages said wedge and forces it against the cylinder, and locks the piston in position, 45 and during its stroke in one direction, forces fluid from the piston into the cylinder; substantially as described.

3. The combination of a cylinder; a hollow 50 piston reciprocating in the cylinder; a chair seat mounted on the piston; a plunger reciprocating in the piston; a fluid passage through the piston; a valve closing said passage, unseatable by pressure within the piston; a fluid passage through the bottom of the plunger; 55 a valve seating upward, closing said passage; and a lever, pivoted to said plunger, and carrying the plunger valve, on one end, and projecting downward at the other; substantially as described.

60 4. The combination in a chair, of a cylinder; a hollow piston reciprocating in the cylinder; a plunger reciprocating in the piston; a fluid passage through the bottom of the plunger; a valve seating upward, closing said passage; a lever pivoted to said plunger, carrying said plunger valve on one end, and having a downwardly projecting part at the other; a fluid

passage through the bottom of the piston; a valve seating inward, closing said passage, and held unseated by said plunger when said 70 plunger is at its lowermost position; substantially as described.

5. The combination of a cylinder mounted upon a base; a hollow piston reciprocating in the cylinder; a fluid passage through the bottom of the piston; a valve for such passage seating upward; a plunger reciprocating in the piston; a lever pivoted between its ends to the bottom of the plunger, and carrying on one end a valve, seating upward, closing said 80 fluid passage, and on the other, a downwardly projecting lug which strikes the bottom of the piston when the plunger reaches a particular point in its down stroke, and opens said valve; substantially as described. 85

6. The combination of a cylinder, having a recess in the inner side thereof; a hollow piston reciprocating in the cylinder, having a head thinner vertically than the height of said recess; a plunger reciprocating in said piston; 90 one or more openings through the side of the piston, above the position occupied by the plunger at the upper end of the plunger's stroke, and which keep the interior of the piston and the space above the head of the plunger, in communication; substantially as described. 95

7. The combination of a cylinder; a hollow piston reciprocating therein; an opening through the side of the piston; a wedge in said 100 opening; a plunger reciprocating in said piston, which engages said wedge and forces it against the cylinder, and locks the piston in position; means which, during the upstroke of the plunger, cause fluid to escape from above 105 the plunger into the space beneath it in the piston; and means which, during the down stroke of the plunger, cause fluid to escape from the piston into the cylinder.

8. The combination of a cylinder; a hollow 110 piston reciprocating therein, having a fluid passage through its bottom, closed by a valve seating upward, and an opening through its side containing a wedge, having its thinnest end lowermost; a plunger reciprocating in said 115 piston, and having a fluid passage through its bottom, closed by a valve seating upward; means opening the plunger valve; and means closing the piston valve on the upstroke of the plunger; means closing the plunger valve; and 120 means opening the piston valve on the down stroke of the plunger; and said wedge being forced into contact with the surface of said cylinder by said plunger, and locked at the end of the extreme upstroke of said plunger; 125 substantially as described.

9. The combination of a cylinder; a hollow piston reciprocating in the cylinder; a fluid passage through the bottom of the piston, closed by a valve seating upward; an opening 130 through the side of the piston, containing a wedge; an annular space above the head of the piston and beneath said wedge; one or more openings which connect said space and

the space above the plunger, when the plunger is in its highest position, and the piston locked in place; and one or more openings which when the piston is in its highest position are near its bottom, and connect the space in the piston below the plunger with said annular space; substantially as described.

10. The combination of a cylinder; a piston reciprocating therein, having an opening through its side with a wedge therein; a plunger reciprocating in the piston, which at the end of its upstroke forces said wedge into contact with the cylinder; a pitman, crooked at its upper end, and connected at its upper end to a crank shaft, through the wrist pin of the crank of said shaft; substantially as described.

11. The combination in a chair of a pair of clamping pieces, located opposite each other, beneath the chair seat, and connected with the chair; one or more springs, tending to force one of said clamping pieces toward the other; an adjustable foot rest; a bar connected with said foot rest and locked by said clamping pieces; and means for enlarging the space between the centers of said clamping pieces; substantially as described.

12. The combination, in a chair, of a crank shaft attached to said chair, and operating a pitman; an adjustable foot-rest; a bar connected therewith; a clutch engaging said bar and locking said foot rest in position; a shaft opening the clutch; a lever rigidly connected to the clutch shaft; and means detachably connecting said crank shaft to said lever, and causing said shafts to move as one; substantially as described.

13. In a chair a shaft, turning in one or more bearings; a lever N attached to the outer end of said shaft, and provided with stops n' , n'' , and containing a bolt n^3 , connected by a rod n^5 to a button n^6 , and pressed upward by a spring n^7 ; and a second shaft, having an arm playing between said stops, and engaged by said bolt; substantially as described.

45 14. The combination of a cylinder; a hollow piston reciprocating therein, having a fluid passage through its bottom; a valve closing said passage; a plunger reciprocating in said piston, which, while at the end of its down stroke, holds the piston valve open; a crank shaft connected with the plunger by a pitman; and a part connected with the crank shaft, which strikes the cylinder when the piston descends, and causes the crank to turn and 55 lift the plunger, leaving the piston valve free to seat; substantially as described.

15. The combination of a cylinder carrying a stop; a piston reciprocating in the cylinder, having a fluid passage through its bottom, closed by a valve; a plunger reciprocating in said piston, having a fluid passage through its bottom, closed by a valve; means whereby said valves are opened by the plunger at about the end of its down stroke; a shaft connected 65 with the plunger and communicating motion to it; an arm projecting from the shaft, carrying a set screw whose end comes in contact

with the stop carried by the cylinder and limits the down stroke of said plunger and the opening of said valves; substantially as described.

16. The combination in a chair of a cylinder; a hollow piston reciprocating in the cylinder, having a fluid passage through its bottom, closed by a valve seating upward; a plunger reciprocating in said piston, having a fluid passage closed by a valve seating upward; and in the presence of a charge of fluid, the piston valve opening, when the plunger is lowered, and closing when it is elevated, and the plunger valve opening when the plunger is raised, and closing when it is lowered, except at about the end of its stroke; means whereby said valves are automatically opened when the plunger reaches the end of its down stroke; a pitman connected to the plunger; a crank shaft operating the pitman; a shaft operating a clutch or clamp; a lever attached thereto; means for connecting and disconnecting the crank shaft from said lever; a chair seat mounted on said piston; an adjustable foot rest connected with said chair seat; a bar pivoted to said foot-rest and extending back from it; and a spring clutch locking said bar in position, except when unlocked by turning said clutch shaft; substantially as described.

17. The combination of a cylinder; a piston reciprocating therein; a plunger reciprocating in the piston; a fluid passage through the bottom of the plunger and a fluid passage through the bottom of the piston, both closed by valves seating upward; the piston valve, in the presence of a charge of fluid, being unseated on the down stroke of the plunger and seating on the upstroke, and the plunger valve being unseated on the upstroke and seating on the down stroke except at about the end of the extreme down stroke, when it is unseated; an opening through the side of the piston; a wedge arranged in said opening, which, at the end of the extreme upstroke of said plunger is forced by said plunger into contact with said cylinder and locks the piston in position; a pitman operating said piston; a tubular crank shaft communicating motion to the pitman; a chair seat mounted on said piston; an adjustable foot rest connected with said chair seat; a rod pivoted to said foot rest and extending back from it a spring clutch by which said rod is locked in position; a shaft passing through said crank shaft by which said clutch is unlocked; and a lever rigidly attached to said inner shaft and detachably connected with said crank shaft; substantially as described.

18. The combination of the shaft L , journaled in bearings, and having the section l^2 screw threaded; a plate M pierced by a screw threaded opening, through which the section l^2 of the shaft L passes, and in which it turns; two upper bolts m , m , and two shorter lower bolts m' , m' ; a plate M' , pierced by a hole through which the shaft L

passes, and connected to the plate M by said bolts; two spiral springs arranged between the heads of said bolts and one of said plates, and pressing it towards the other plate; a 5 transverse groove across the inner face of each of said plates, said grooves being substantially opposite each other and parallel; an adjustable foot rest, having a bar pivoted thereto at one end and projecting backward 10 and passing between said plates and its sides entering said grooves; and said bar being locked in position by the force of said springs, and unlocked by turning said shaft L far enough to bring the shoulder at the inner end 15 of the screw threaded section against the inner face of the opposite plate, and forcing the plates apart; substantially as described.

19. The combination of a cylinder; a hollow piston reciprocating therein, having the 20 head f, the annular recess f' above its head, one or more fluid passages f² and f³, connecting said recess with the interior of the piston; an opening f⁴ through the piston; a wedge f⁵ in the opening f⁴; the hollow plunger H, having a fluid passage h⁵ through its bottom; and a lever H' pivoted to its bottom, and carrying on one end a valve h⁷ which closes the passage h⁵ when seated, and at its other end carries a downwardly projecting part, and is 25 sufficiently heavy to seat said valve; an annular recess h¹¹ connected with the interior of the plunger by fluid passages h⁴; and the recess h¹² adapted to receive the inner side of said wedge; and means for operating said 30 plunger; substantially as described.

20. The combination in a chair of an adjustable foot-rest; a pair of clamping pieces,

connected to the chair beneath its seat; a part connected with the foot rest, extending between said clamping pieces, and held thereby; 40 one or more springs pressing against the back of one of said plates, and forcing them to engage said part extending between them; and a revoluble shaft forcing said plates apart; substantially as described. 45

21. The combination in a chair of an adjustable foot-rest; a bar pivoted to said rest, and extending back therefrom; a pair of clamping pieces, pivotally attached to said chair, opposite each other, beneath the chair 50 seat, in position to permit said bar to pass between them; means tending to force said pieces together; and means for forcing them apart; substantially as described.

22. In a chair an adjustable foot rest; means 55 carried by the chair, locking said foot rest in position; a pitman beneath the chair seat; a tubular shaft operating the pitman; one or more bearings, attached to the chair, supporting the tubular shaft; a shaft passing through 60 the tubular shaft, and operating the foot-rest lock; a lever rigidly attached to said central shaft, carrying two stops, having a space between them; a crank attached to the tubular shaft, located and movable between said stops 65 carried by said lever; and means detachably and rigidly connecting said crank to said lever, and causing said shafts to move as one; substantially as described.

Witness my hand this 9th day of May, 1895. 70
